UNITED STATES PATENT OFFICE.

JOHN F. CAVANAGH, OF PROVIDENCE, RHODE ISLAND, ASSIGNOR OF THREE-FOURTHS
TO LINDSLEY AND ALLEN ELECTRIC COMPANY, OF PROVIDENCE, RHODE ISLAND,
A CORPORATION OF RHODE ISLAND.

ELECTRIC REVERSING-SWITCH.

972,999.

Specification of Letters Patent.

Patented Oct. 18, 1910.

Application filed November 5, 1908. Serial No. 461,115.

To all whom it may concern:

Be it known that I, JOHN F. CAVANAGH, a citizen of the United States, residing at the city of Providence, in the county of Providence and State of Rhode Island, have invented certain new and useful Improvements in Electric Reversing-Switches, of which the following is a specification, reference being had therein to the accompanying drawings.

This invention relates to a reversing switch for spark coils, and has for its object to provide simple and effective means whereby the direction of travel of the current through the contact points of the vibrator coils may be changed each time the connection is made after having been broken.

In practice the contact points on vibrator coils are usually made of platinum, iridium, or other metal adapted to resist oxidization and fusing. As the current passes through the coil from one point to the other, as said points are rapidly vibrated, small particles of the metal leave the point of the positive pole, which point soon becomes pitted or worn away, said particles being deposited on the point of the negative pole, which becomes correspondingly built up or elongated. The points thus work out of adjustment and as they become roughened and deteriorated the coil loses its effectiveness or efficiency, in order to restore which new points have to be set, or the old ones stoned, evened up or dressed and the vibrator adjusted or re-set. Heretofore in order to equalize the effect of the current on both of the points, the direction of said current is sometimes changed by reversing the battery connections, but in the case of operating automobiles, motor boats, and the like, where the majority of these devices are used, this is seldom resorted to as the cause and effect is not generally understood by the operators. In order to obviate this serious difficulty and provide simple, practical and effective means whereby the current may be reversed each time the connection is made after having been broken, I have provided a switch which automatically changes the connections to reverse the direction of the current, each time the same is operated. I have also provided a simplified form of this

device which is in the form of a removable plug whereby the direction of the current is reversed by a proper positioning of said plug in its socket.

With these objects in view, the invention consists of certain novel features of construction, as will be more fully described and particularly pointed out in the appended claims.

In the accompanying drawings: Figure 1— is a plan view showing the arrangement of mechanism whereby the direction of the current is automatically changed each time a new connection is made by a movement of the switch into the operative or contact position. Fig. 2— is a front detail view of the switch lever with the mechanism removed therefrom. Fig. 3— is a side elevation of said switch lever showing the rotary ratchet disk which carries the contact points mounted on said lever. Fig. 4— is a plan view of the rotary ratchet disk in detail. Fig. 5— is an enlarged section of said disk on line 5—5 of Fig. 4. Fig. 6— is an enlarged section on line 6—6 of Fig. 4. Fig. 7— is a diagrammatic view showing the wiring and the direction of travel of the current when the rotary disk is in the position indicated in Fig. 5. Fig. 8— is a diagrammatic view illustrating the travel of the current when the disk is in the position illustrated in Fig. 6, the travel of the current through the carbureter and spark coil being in the opposite direction to that illustrated in Fig. 7. Fig. 9— is a perspective view of spark coil switch casing showing the switch plug in one position in the casing. Fig. 10— is a transverse sectional view showing the switch plug in position in the casing. Fig. 11— is a section through the switch casing with the top removed showing the terminals which are adapted to be bridged by means of plates on the switch plug. Fig. 12— illustrates the plug having transversely arranged bridge plates. Fig. 13— represents the opposite side of the plug where the bridge plates run lengthwise thereof. Fig. 14— is an edge view of said plug. Fig. 15— is a transverse section on line 15—15 of Fig. 14. Fig. 16— is a detail in perspective illustrating the construction of the bridge plates. Fig. 17— is a dia-

- grammatic view illustrating the direction of current through the interrupter and coil when the plug is placed in position, having its transverse plates bridging the terminals.
- 5 Fig. 18— is a diagrammatic view illustrating the wiring of the device showing the travel of the current in the reverse direction through the coil and interrupter when the plug is placed in position, with its length-
10 wise bridge plates in contact with the terminals.
- It is found in practice in the use of spark coils advantageous to employ two sources of current such as a battery and a magneto, or
15 two separate sets of batteries, one for reserve to be used in case of emergency, and the switch in question is adapted to readily make connection with either of said sources as desired.
- 20 In carrying out my invention 1 designates the circular switch casing which may be made of any suitable non-conducting material such as rubber or the like, and in which casing a switch lever 3, preferably of
25 conducting material is pivoted at its upper end on a hollow pivot 7 adapted to receive a pin 8, which is passed therethrough to complete the circuit through the spring contact piece 9, said pin being adapted to be re-
30 moved to break the circuit to prevent the motor from being started until it is returned to position. The lower end of said lever projects out beyond the circumference of the casing and is provided with an operating
35 handle 4 whereby the same may be moved from the center or neutral position, indicated at A, to either side of the center, as indicated at B and C, whereby a connection may be made to either of said sources of cur-
40 rent to operate the sparking device, not shown, through the interrupter 5 and coil 6. Pivotaly mounted at 10 to rotate on this switch lever is a ratchet wheel 11, which is preferably made of non-conducting ma-
45 terial. Secured to opposite sides of this wheel are two corresponding bridge plates 12 and 13, each being provided with four contact points 14—14, said plates being electrically insulated from each other. Located
50 between these points 14 are four contact or bridge pins 15—15 which extend through said ratchet wheel 11 to electrically connect the corresponding points on opposite sides thereof when said disk is in predetermined
55 positions. This lever 3 is provided with laterally extending resilient contact ears 3^a which are slightly concaved or cupped on their engaging faces to receive the heads of the said contact or bridge points and pins 14
60 and 15 to prevent the same from being inadvertently moved when in their operative position.

The three spring contact fingers 16, 17 and 18 on one side and a corresponding set
65 19, 20 and 21 on the opposite side of the

switch casing, working in conjunction with the contact points 3^a on the switch casing, serve as the wire terminals, which terminals are bridged when the switch lever is in its operative position either by the bridge 70 plates 13 and 14 or by the bridge pins 15—15 to complete the circuit and cause the electric current to pass through the coil and interrupter either in one direction or the other. Each time the switch lever is moved from 75 the center or neutral position to either of the operating positions and back again, the pawl 22, which is pressed into engagement with the teeth of the ratchet by spring 23, causes said ratchet wheel to rotate and 80 change the position of contact points 14 and 15 to reverse the direction of the current through the interrupter. As illustrated in Fig. 7 when the rotary ratchet wheel and its bridge points are in the position illustrated 85 in Fig. 5, the current passes from the battery or other source of current 24 in the direction of the arrow through contact 16, across bridge plate 13, contact 3^a, switch lever 3, through the interrupter 5 and coil 6, 90 wires 25 and 27 around through contact 17, bridge plate 12, contact 18, wire 28 back to battery 24, but when the ratchet disk is rotated by the next stroke of the switch lever the bridge pins 15 are brought into operative 95 position and the current then leaves battery 24 in the direction of the arrow and passes from contact 16 through bridge pin 15 to contact 17, back through wire 27, thence by wire 25 through coil 6 and interrupter 5 in 100 the opposite direction from that illustrated in Fig. 7 back through switch lever 3, contact 3^a, bridge pin 15, to contact 18, then by wire 28 back to battery 24. A similar wir-
105 ing is arranged for the other set of batteries or magneto, which may be connected by simply throwing the switch lever to the oppo-
110 site side of the center A.

A modified form of my improved switch is illustrated in Figs. 9 to 18 inclusive, in 110 which the switch is composed of a casing 29 provided with three plug receiving openings 30, 31 and 32, openings 30 and 32 being equivalent to positions B and C in Fig. 1, while opening 31 is the neutral position, 115 equivalent to position A in Fig. 1, in which position the plug may be placed when neither of the batteries are to be connected. This switch is composed of four terminals 33, 34, 35 and 36 for connecting one set of batteries, and terminals 37, 38, 39 and 40 for connecting up the second set of batteries or magneto. The plug 41, as best illustrated in Figs. 12 and 13, is constructed of insu-
120 lating material. On one of its faces are two transverse bridge plates 42—43 spaced apart a distance corresponding to the terminals in the switch casing and are adapted to connect or bridge said terminals in the manner illustrated in Fig. 17. On the op-
125 130

posite side of this plug the bridge plates 44 and 45 run lengthwise of the block and are adapted when placed with their faces against the terminals to connect the same up in the manner illustrated in Fig. 18. In order to facilitate the construction of these bridge plates they are made up in the manner illustrated in Fig. 16, one longitudinal plate 45 and one transverse plate 43 being made up of a single piece of material, the same being connected together around the edge of the plug by the connecting portion 46. The wiring of this simplified construction is substantially the same as illustrated in Figs. 7 and 8, the current passing from battery, or other source of current, 47 through wire 48, from terminal 33, across bridge 42 to terminal 34 and wire 49 to interrupter 5, coil 6, wire 50, wire 52 to terminal 35 across bridge 43, terminal 36, wire 53, back to the battery, while when the plug 41 is placed with its other face in contact with the terminals the circuit starts from the battery 47, wire 48, from terminal 33 across bridge 44 to terminal 35, along wire 52, wire 50 through coil 6, interrupter 5, wire 49 to terminal 34 across bridge 45 to terminal 36, wire 53 back to battery. It will be seen by reversing this plug or the bringing of its opposite faces against the terminals that the direction of the current is changed through the interrupter and coil. When it is desired to use the second set of batteries the plug is placed into the socket 30 thus connecting up the terminals 38, 39 and 40 in a similar manner to that above described.

Manually operated switches heretofore employed in controlling electric currents through an interrupter and coil have always allowed the current to pass in one or the same direction through the interrupter points, whereby small particles would leave the positive point of the interrupter causing pitting and cutting out, and forming a cup-shaped recess in the end of the positive point similar to the effect of current passing through the carbon of an arc lamp, the result being that these particles pass with the current and are deposited onto the negative point thus building up this latter point in a rough manner and throwing the whole coil out of adjustment and materially reducing its efficiency. By the use of one construction of my improved device the direction of travel of the current is automatically reversed each time the motor is started, thus positively insuring an equalization of the deteriorating effect on the points, or by the use of my simplified form of switch plug the reversing of the current may be accomplished as often as desired, causing the points to last practically for an indefinite time with little or no attention, and as they are thus kept in practically perfect condi-

tion the coil is caused to produce its maximum efficiency.

The device is extremely simple and practical in construction and effective in its operation.

Having thus described my invention, what I claim as new and desire to secure by Letters Patent, is:

1. A switch of the character described comprising a casing provided with oppositely disposed sets of contacts, an arm pivotally mounted to swing between said contacts and also provided with contacts, and means for shifting the contacts on said arm to reverse the current passing through the contacts in said casing. 75

2. A switch of the character described comprising a circuit having contact terminals, an arm mounted to swing between said terminals and provided with contacts, and means for automatically shifting said contacts each time said arm is swung, whereby the current is reversed through said circuit. 85

3. A switch of the character described comprising a circuit provided with contact terminals, an arm mounted to swing between said terminals and provided with a rotatable member having contacts, and means for automatically rotating said member as said arm is swung to reverse the direction of current 95 through said circuit.

4. A switch of the character described comprising a circuit provided with contact terminals, an arm mounted to swing between said terminals, a rotatable member mounted on said arm and provided with contacts, means for automatically rotating said member as said arm is swung, and independent contact plates carried by said rotatable member. 100

5. A switch of the character described comprising a circuit having contact terminals, an arm mounted to swing between said terminals, a rotatable member mounted on said arm and provided with contact pins extending therethrough, means for automatically rotating said member as said arm is swung, and independent contact plates mounted on said rotatable member. 110

6. A switch of the character described comprising a circuit provided with contact terminals, an arm mounted to swing between said terminals, a ratchet wheel constructed of insulating material rotatably mounted upon said arm and provided with contact pins, independent contact plates mounted on said ratchet wheel, and a stationary tool engaging said ratchet wheel. 115

7. A switch of the character described comprising an electric circuit provided with contact terminals, an arm mounted to swing between said terminals, a member rotatably mounted on said arm and provided with contacts, means for automatically rotating said member as said arm is swung, and sta- 125

tionary contacts carried by said arm, said arm being included in said circuit, and means for breaking said circuit.

8. In an electric switch, a plurality of terminals, a switch arm, a rotatable disk mounted on said arm, two distinct sets of bridging members on said disk, means for automatically rotating said disk each time said arm completes a stroke to and from its operating position whereby the connections between the terminals are changed to reverse the direction of the current.

9. In an electric switch, a plurality of terminals, a switch arm, a rotatable ratchet

disk mounted on said arm, two separate sets of bridging members carried by said disk, a pawl adapted to engage said ratchet to rotate the same as said arm is moved to complete its stroke whereby the connections between the terminals are changed to reverse the direction of the current.

In testimony whereof I affix my signature in presence of two witnesses.

JOHN F. CAVANAGH.
